INSTALLATION TOOL FOR CASING
PROTECTORS

James F. Medearis, Ventura, Calif.

Application September 18, 1948, Serial No. 49,972

6 Claims. (Cl. 254—66)

1

This invention relates to oil well equipment and particularly pertains to installation tools for casing protectors.

In the form of casing protector disclosed in my co-pending application filed concurrently herewith I have shown a resilient protector sleeve which is split longitudinally along a parting plane, the free edges of said split portion carrying plates which interlock to hold the sleeve under tension and in an embracing position around the drill string. In order to apply the protector sleeve to the drill pipe it is necessary to positively engage the sleeve at opposite sides of said parting plane and to draw said free portions of the sleeve together in a manner to cause the interlocking means to engage and hold the sleeve. It is the principal object of the present invention to provide an installation tool by which the sleeve may be engaged and by which power may be applied to draw the sleeve into an embracing position around the drill pipe with the contiguous faces of the sleeve wall at the parting plane in abutting relation with each other and in a manner to cause the latch means to become engaged.

The present invention contemplates the provision of an arcuate device adapted to conform to the outer cylindrical contour of a casing sleeve and to positively engage the same at points therealong, said device including means whereby power may be applied to draw the abutting faces of the casing wall together and produce engagement of the interlocking means.

The invention is illustrated by way of example in the accompanying drawings in which:

Figure 1 is a view in elevation showing the installation tool with which the present invention is concerned.

Fig. 2 is a view in transverse section through the tool as shown on the line 2—2 of Fig. 1 indicating its operating mechanism and further indicating a casing protector by dotted lines.

Referring more particularly to the drawing, 10 indicates a cylindrical casing protector having a resilient wall of uniform thickness. At one point in the circumference of said wall the wall is split along a parting plane which is defined by a radially extending outer portion 11 and an obliquely extending inner portion 12. Imbedded within the free edges of the wall at opposite sides of said parting plane are latch plates 13 and 14 fitted with hook portions 15 and 16, respectively. These hook portions are complementary and extend across the plane of the parting portion 12 so that they may be moved into interlocking engagement with each other. The plates 13 and 14 are formed with perforations 17 which are intersected by pockets or openings 18 formed in the resilient wall of the casing protector 10. The present invention is concerned with means for drawing the contiguous edges of

10 said wall together and interlocking the plates 13 and 14. The structure comprises an arcuate gear segment 19 having teeth 20 along the outer edge thereof. A bar 21 is secured to one end of the segment 19 and extends parallel to the axis of the gear segment. This bar is of a length substantially agreeing in length with that of the protector sleeve 10. As shown in Fig. 1 of the drawing the bar is fitted with a plurality of pins 22. These pins agree in number and position with the openings or pockets 18 formed throughout the length of the protector sleeve 10. The dimensions of the bar 21 are such as to space the inner arcuate face of the segment 19 from the circumference of the protector sleeve 10 when the inner face of the bar 21 rests against the outer circumference of the sleeve 10 and is disposed lengthwise thereof. Secured to the arcuate segment 19 at a point intermediate its ends and 15 spaced from the bar 21 is a bar 23. This bar carries a plurality of pins 24 which agree in spacing with the pins 22. A frame structure 25 is secured to the bar 23 and is formed with a bearing or guideway 26 through which the segment 19 extends and along which it may move. A lower wall section 27 having an upper arcuate face provides a retaining support for the segment 19. The frame structure has opposite end walls 28 and 29 which are spaced from each other and side 20 walls 30. In the space between the end and side walls a ratchet arm 31 is disposed. This arm is pivotally mounted upon a ratchet gear pin 32. Freely mounted upon the pin 32 is a ratchet gear 33. The teeth of the ratchet gear 33 engage the teeth 20 on the segment 19. The ratchet arm 31 carries a pawl 34 which is pivoted upon a pin 35 and has a tooth 36 at its free end to engage the teeth of the ratchet gear 33. A spring 37 yieldably holds the tooth 36 of the pawl 34 in engagement with the ratchet gear 33. A lock pawl 38 is pivoted upon a pin 39 in the frame 29 and has a tooth 40 which engages the teeth of the ratchet gear 33. The pawl 38 also has an extension against which a spring 41 acts. This tends to urge the tooth 40 into engagement with the teeth of the ratchet gear 33 and will hold the ratchet gear 33 from moving while the pawl 34 is acting to rotate the gear 33. At the free end of the ratchet arm 31 is a socket 42 to receive a handle 43 by which the arm 31 may be oscillated. Mounted upon the frame 29 at 44 is another socket by which a handle 45 may be held. In operation of the present invention the casing protector is placed in an embracing position around a drill pipe by spreading it along its parting plane. After this has been accomplished the pins 22 and 24 may be inserted in the openings or pockets 18 and pressed inwardly until they pass through the perforations 17 in the plates 13 and 14. The frame structure 29 may be then held

firmly by the handle 45 and the arm 31 may be caused to oscillate around the pin 32. The spring 37 will hold the tooth 38 of the pawl 34 in engagement with a tooth on the ratchet gear 33, and as the arm 31 is moved by its handle 43 in the direction of the arrow *a* the ratchet gear 33 will move in the direction of the arrow *b*, as indicated in Fig. 1. This will tend to pull the gear segment 19 in the direction of the arrow *c*, as indicated in Fig. 1, and when the end of the stroke of the arm 31 has been completed the tooth 40 of the pawl 38 will engage a tooth of the ratchet gear 33 and hold the gear 33 and the segment 19 in their tightened position. This will draw the pins 22 and 24 toward each other and force the hook portions 15 and 16 of the plates 13 and 14 into an interlocking relation as the sleeve is pulled tightly around the drill pipe and the abutting portions 11 and 12 along the parting plane are forced together. When the portions 15 and 16 have been interlocked the segment 19 may be released by pressing on the extension of the pawl 38 to withdraw the tooth 40 from engagement with the teeth on the gear 33. The tool may be then instantly withdrawn from engagement with the sleeve.

It will thus be seen that with the structure here disclosed resilient casing protectors may be easily positioned upon a drill pipe at any desired point along the length thereof and then rigidly clamped in this position by simple and effective power applying means.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. An installing tool for applying a tubular cylindrical casing protector to a drill pipe, said protector being split longitudinally at a point in its circumference and being formed with pockets extending through its outer circumference adjacent to said split, the tool comprising a pair of pull bars, each bar carrying pins to extend into the pockets on the casing protector, an arcuate gear segment partially circumscribing said protector and to which one of said pull bars is fixed, a frame structure, means movably mounting said gear segment whereby the latter moves circumferentially of the casing protector, the other of said pull bars being fixed to the frame, a gear carried by the frame and in mesh with said segment, and power applying means for driving said gear and moving said segment whereby the pins will tend to draw the contiguous edges of the casing protector together.

2. An installing tool for applying a tubular cylindrical casing protector to a drill pipe, said protector being split longitudinally at a point in its circumference and being formed with pockets extending through its outer circumference adjacent to said split, the tool comprising a pair of pull bars, each bar carrying pins to extend into the pockets on the casing protector, an arcuate gear segment partially circumscribing said protector and to which one of said pull bars is fixed, a frame structure, means movably mounting said gear segment whereby the latter moves circumferentially of the casing protector, the other of

said pull bars being fixed to the frame, a gear carried by the frame and in mesh with said segment, an operating lever oscillating around the axis of said gear, and ratchet means carried by the operating lever to rotate the gear as the lever oscillates whereby the gear segment will be moved and the pins on the pulling bars will be drawn toward each other.

3. The structure of claim 2 including latch means acting to temporarily hold the ratchet gear against reverse rotation.

4. A tool of the character described comprising a frame formed with an arcuate guide slot through it, an arcuate gear segment adapted to move through said guide slot, said gear segment having a series of teeth along its outer circumference, a ratchet gear rotatably mounted within the frame and meshing with the teeth of the gear segment whereby the segment will be held within its slot and will be moved as the ratchet gear rotates, a lever arm mounted within the frame to oscillate around the axis of the ratchet gear, a pawl carried by the lever arm to engage the ratchet gear and rotate the same as the arm oscillates in one direction, a pawl carried by the frame structure and engaging the ratchet gear to latch it against rotation in the opposite direction, a pull bar fixed to the frame and carrying a series of pins spaced throughout the length thereof and disposed radially of the axis of the gear segment, and a pull bar fixed to the gear segment and carrying a series of pins extending radially of the axis of the gear segment, whereby upon oscillation of the lever arm the pins will be moved simultaneously with relation to each other.

5. An installing tool for applying a tubular cylindrical casing protector to a drill pipe, said protector being split longitudinally at a given point throughout its length and being formed with pockets in its contiguous edges, said tool including: an arcuate element; an arcuate bearing in which said arcuate element is adapted to slide; pins on said element and said bearing which are adapted to be extended into said pockets when said tool is shifted into operative relation with said casing protector and said pipe, the curvature of said element and said bearing being so formed as to be substantially concentric with said pipe when said tool is so positioned; and power means for causing relative rotation between said element and said bearing concentric with said protector, with the tool so positioned, to exert a pull on the contiguous edges of said protector to contract the latter about said pipe.

6. A combination as in claim 5 in which said element is in the form of a gear segment, and in which said power means includes a pinion rotatably mounted on said bearing so as to mesh with said gear segment; and manually operable ratchet means mounted on said bearing for transmitting tooth by tooth rotation to said pinion wheel and thereby sliding said element in said bearing to constrict said casing protector about said pipe.
